HAM BOILER

Hans Reinwald, New York, N. Y.

Application December 10, 1938, Serial No. 244,889

3 Claims.

(Cl. 53—22)

This invention relates to ham boilers, that is, containers in which hams are adapted to be pressed and sealed, and aims to provide a ham boiler which may be readily used either for hand or machine pressing, and which at the same time embodies novel features and improvements such as, for instance, efficient restriction of the meat juices within the sealed boiler.

The above and other objects will become apparent in the description below, in which characters of reference refer to like-named parts in the accompanying drawings.

Referring briefly to the drawings, Figure 1 is a plan view of the boiler adapted for machine pressing.

Figure 2 is a cross-sectional view taken on the line 2—2 of Figure 1.

Figure 3 is a fragmentary end elevational view of the same.

Figure 4 is a cross-sectional view taken on the line 4—4 of Figure 2.

Figure 5 is a cross-sectional view taken on the line 5—5 of Figure 2.

Figure 6 is a longitudinal cross-sectional elevational view of the boiler adapted for hand pressing.

Referring in detail to the drawings, the numeral 10 represents a vat-like container open at the top and provided in its upper peripheral edge 30 with a groove 11. A press board 12 is adapted to slide vertically within the container 10 in the fashion of a piston in a cylinder, and is provided with a depending peripheral flange 13.

A sealing cover 14 has a peripheral depending bead 15 adapted to register in the groove 11, and intermediate its length has a pair of spaced vertical openings 16 therethrough. Raised flanges 17 surround the openings 16 on the top of the cover 14. A cross-beam 18 has at each end a recess 19 on its underside, in which the head of a stud 20 is pivotally suspended by a pin 21 extending at right angles to the beam 18. Each stud 20 is provided with a vertical row of serrations 22 on its outer side. These studs extend slidably through the openings 16 and at their lower extremities are pivotally secured at 23 to the board 12.

Between the opening 16 and the end of the cover, at each end of the latter, slots 24 are provided, which are open at the top and which extend into the openings 16. A sharpened or pointed tongue 25 is slidably mounted in the slot 24, and a spring 26 normally urges the tongue 25 into the opening 16. The tongue is provided with an upward extending ear 27 which rises above the

surface of the cover, so that the finger of the operator may be readily applied thereto to move the tongue out of engagement with the serrated side of the stud 20. It is to be noted that the sharpened edge of the tongue 25 is at such an angle as to permit depression of the stud 20 through the opening 16 but to prevent withdrawal upward of the stud, in the manner of the familiar ratchet and pawl.

Slotted extensions 28 are provided on the ends 10 of the cover, adapted to receive the upper ends of screw bolts 29 pivoted at their lower ends on ears 30 on the end walls of the container 10. Wing screws 31 serve to clamp the cover tight against the container.

In using this form of ham boiler, the beam 18 is secured to the machine which presses the same downward, and the board 12 will remain locked in the lowermost position into which it is pressed. After the ham has been boiled, the board is released by withdrawing the tongues 25, and the cover is then removed in an obvious manner.

When the ham is to be hand pressed in the boiler, the same container 10, the same press board 12, and the same cover 14a, may be used, although for the sake of simplicity the cover 14a shown in Figure 6 omits duplication of the showing of the tongues 25, especially since the latter are not necessary for the construction shown. Other parts in Figure 6 which are identical to those of the other figures have been similarly numbered.

Instead of the beam 18 and its pivoted studs 20, a pair of mutually independent screw threaded studs 32 are threadably inserted into the openings 16. It is to be noted that the latter are internally screw threaded in both covers 14 and 14a, although this fact was not heretofore mentioned because the threads in the cover 14 do not function as such.

The lower ends of the studs 32 are of a modified construction to permit rotation of the studs, as is obviously necessary. To accomplish this end, a nipple 33 is formed on the end of the stud 32 and provided with a peripheral groove 34. This nipple registers rotatably in a collar 35 having one or more set screws 36 passing through its side into engagement with the groove 34. The collar 35 is rigid on an ear 37 which is pivotally mounted at 23 on the board 12. The operation of this hand press form is obvious. Likewise, the changing of the boiler from a machine press to a hand press type or vice versa, is also apparent, and the changing over can be accomplished in a short interval of time.

55

55

Obviously, modifications in form and structure may be made without departing from the spirit and scope of the invention.

I claim:

- 5 1. A ham boiler comprising a container open at the top and having a press board vertically slidable therein, a cover having means for clamping the same on the container, said cover having spaced apart openings therethrough, studs in said 10 openings vertically moveable in either direction therethrough, means partly on said cover and partly on said studs for releasably locking said studs in said openings intermediate their length, the lower ends of said studs being pivotally secured to said board.
- 15 2. A ham boiler comprising a container open at the top and having a press board vertically slidable therein, a cover having means for clamping the same on the container, said cover having spaced apart openings therethrough, studs slidably mounted in said openings, a beam above said

cover having the upper ends of said studs pivotally secured thereto, said studs having serrations thereon, latch bolts slidably mounted in said cover adjacent said openings and having resilient means normally urging the same into engagement with said serrations, the lower ends of said studs being pivotally secured to said board.

5 3. A ham boiler comprising a container open at the top and having a press board vertically slidable therein, a cover having means for clamping the same on said container, said cover having spaced apart threaded openings therethrough, threaded studs passing through said openings, each of said studs having a nipple on its lower end and a collar rotatably surrounding said nipple, said nipples each having a peripheral groove, said collars each having set screws passing therethrough into said groove, said collars being pivotally secured to said board.

10 15 20 HANS REINWALD.
